UNITED STATES PATENT OFFICE.

CHARLES F. PFLANZE, OF ST. LOUIS, MISSOURI.

MACHINE FOR MAKING WINDOW-ENVELOPS.

1,361,545.

Specification of Letters Patent.

Patented Dec. 7, 1920.

Application filed October 8, 1917. Serial No. 195,293.

To all whom it may concern:

Be it known that I, CHARLES F. PFLANZE, a citizen of the United States of America, a resident of the city of St. Louis, in the State 5 of Missouri, have invented certain new and useful Improvements in Machines for Making Window-Envelops, of which the following is a full, clear, and exact description, reference being had to the accompanying 10 drawings, forming a part of this specification.

This invention relates to an improved machine for making window envelopes, one of the objects being to firmly secure transparent patches to the margins of the windows. This is accomplished by maintaining the patch and a gummed envelop blank under pressure for a considerable period of time, thereby causing the patch to adhere firmly 15 to the gummed margins of the window. The patch and the envelop blank are preferably maintained under pressure between two flat plates, larger in area than the patch, so that the prolonged pressure is obtained 20 at all of the gummed margins of the window.

Another object is to accomplish the foregoing result while the window envelop blank is in motion, traveling from one part of the 25 machine to another, so that the successive envelop forming operations can be performed continuously, without being delayed by the patch-pressing operations. The several operations, such as gumming, creasing 30 and folding the envelop blanks, can be performed most conveniently by keeping the blanks in motion, continually feeding them from one device to another, so as to avoid the delays which would otherwise be caused 35 by stopping the blanks at the different devices.

I therefore maintain the gummed blank and patch under pressure, while they are traveling through the machine. During the 40 pressing operation, the flat pressure plates travel with the blank and patch, so the motion of the blanks through the machine will not be retarded by the prolonged pressure to which the blank and patch are subjected.

50 I do not deem it necessary to show any means for performing the operations of folding and creasing the window envelop blank. The present invention relates entirely to a method of and means for applying patches to the envelop windows, and the other elements of the envelop making

apparatus may be constructed in any suitable manner.

Figure I is a vertical section of a portion of an envelop making machine, showing the 60 new patch applying devices.

Fig. II is an enlarged front elevation, partly in section, showing the upper portion of the machine.

Fig. III is a vertical section taken approximately through the center of the structure shown in Fig. II.

Fig. IV is a diagrammatical view showing the revolving pressure members and an envelop blank arranged between two of said 70 members.

Fig. V is a view similar to Fig. IV, showing the envelop blank pressed between two of the pressure members.

Fig. VI is a side elevation of the machine, 75 showing the driving mechanism.

Fig. VII is a detail view of the gumming roll.

Fig. VIII is a view similar to Fig. IV, 80 illustrating a modification.

To illustrate the invention I have shown a pressing device including flat pressure plates 1 and 2 secured to rotary carriers A and B, respectively. Each of the rotary carriers comprises arms 3 supported by a 85 stationary shaft 4, and the flat pressure plates are pivoted, at 5, to said arms 3, the pivots passing through flanges which extend from the pressure plates. The pressure plates revolve about the axes of the stationary shafts, as will be hereinafter described, and said pressure plates are free to turn on their pivots 5 so as to lie parallel with each other during the pressing operation, as shown in Fig. V. The envelop 90 blank, passing to the pressure plates, travels in the path indicated by arrows in Fig. I. It travels from a pair of rotating feed rolls 6, to a gumming roll 7 arranged above a feed roll 8, and thence to the pressure 100 plates. The window envelop blank is designated by the character X in Figs. IV and V, and the gumming roll 7 is shown most clearly in Fig. VII. A gum receptacle 9 (Fig. I) is provided with a gum delivering 105 roll 10 contacting with a gum transferring roll 11, the latter being in contact with a roll 12 whereby the gum is transferred to the roll 7. This gumming roll 7 (Fig. VII) is provided with raised surfaces 13 and 14 110 whereby the gum is received from the transferring roll 12 and impressed upon the en-

velop blanks. The surfaces 14 impress the gum upon the flaps of the envelop, and the rectangular surface 13 impresses gum around the margins of the window in the envelop blank.

The transparent patches for the window openings are obtained from a roll of transparent tape 15 located at the upper portion of the machine. The transparent strip 10 passes between feed rolls 16, each of which is provided with a blade 17 and a blade receiving recess 18. The rolls 16 are driven continuously for the purpose of feeding the transparent strip and at the same time cutting 15 it into relatively small patch members which are eventually secured to the gummed margins of the window in the envelop blank. Each blade 17 is adapted to enter the recess 18 in the companion roll, and two patches 20 are therefore severed from the transparent strip during each revolution of the rolls 16.

The means for transferring the patches from the rolls 16 to the pressure plates 1 comprises an oscillatory transferring arm C 25 associated with gripping fingers 19 on the pressure plates 1. The transferring arm C oscillates about the axis of a stationary shaft 20 for the purpose of carrying the patches to the gripping fingers 19, and the latter serve 30 as means for securing the patches to the pressure plates 1. The transferring arm C includes a main arm member 21, loosely mounted on the shaft 20, and provided at its lower end with a gripping jaw 22. This 35 gripping jaw 22, shown most clearly in Figs. II and III, is rigidly secured to the arm member 21. A gripping jaw 23, located directly above the jaw 22, is rigidly secured to the lower end of a latch bar 24, the latter being slotted at 25 to receive screws 26 and 27 which extend into the main arm member 21. The screws 26 and 27 pass through the elongated slots 25 and are firmly secured to the arm member 21. The latch bar 24 is 40 thus loosely connected to the arm member 21, and said latch bar may be actuated to move its jaw 23 toward and away from the jaw 22. 28 designates a pin (Fig. II) secured to the latch bar 24 and extending through a slot 29 in the arm member 21. A spring 30 connects the pin 28 to a pin 31 on the arm 21. This spring 30, pulling upwardly on the latch bar 24, tends to lift the jaw 23 from the jaw 22. However, the jaws are temporarily 45 locked in their closed positions, as shown by full lines in Figs. II and III. A latch dog 32, pivotally supported by the screw 27 cooperates with a lug 33 extending from the latch bar 24 to retain the latter in the position shown by full lines in Figs. II and III. The spring 30 (Fig. II) tends to lift the latch bar 24, and a movement of this kind is prevented by the lug 33 which extends from the latch bar and lies under a shoulder on the 50 latch dog 32. It will now be understood that

if the latch dog 32 is disengaged from the lug 33, the spring 30 will lift the latch bar 24 so as to open the gripping jaws.

34 designates a spring (Fig. III) connecting the latch dog 32 to a pin on the arm 21, 70 and tending to retain said latch dog in engagement with the lug 33. If the latch dog 32 is released from the lug 33, the latch bar 24 will be lifted, as just pointed out, and if the latch bar 24 is again depressed, to close the 75 jaws, the spring actuated latch dog 32 will again coöperate with the lug 33 to retain the jaws in their closed positions. In opening the gripping device a stationary abutment pin 35 is utilized to disengage the dog 32 80 from the lug 33, as will be presently described.

36 designates a stationary cam fixed to the stationary shaft 20 and located in the path of a roller 37 at the upper end of the latch bar 85 24. A constantly rotating cam 38, fixed to a shaft 39, is provided with a cam groove 40 for the reception of a roller which extends from an arm 41, the latter being formed integrally with the main arm member 21. 90 The transferring device, comprising the main arm member 21 and the various parts secured thereto, oscillates about the axis of the stationary shaft 20 in response to the rotary movement of the cam 38. When 95 the transferring device occupies the position shown by dotted lines in Fig. III, its jaws 22 and 23 are approaching the transparent patch Z passing from the rolls 16. At this time the jaws 22 and 23 are open to 100 receive the patch, but as they continue to approach the patch the roller 37 rides outwardly on the stationary cam 36 so as to actuate the bar 24, thereby forcing the jaw 23 toward the jaw 22. The jaws are thus closed 105 to grip the patch X, and they are locked in their closed positions by the spring actuated latch dog 32 and the lug 33. When the transferring device reaches the position shown by full lines in Fig. III, the latch dog 32 110 strikes the stationary abutment pin 35 and passes from the lug 33, thereby permitting the spring 30 (Fig. II) to lift the bar 24 and its gripping jaw 23. The gripping device is thus opened to deliver the transparent 115 patch to the pressure plate 1. Thereafter, the transferring device continues to move in the direction indicated by the arrow in Fig. III, so as to pass out of the path of the gripping plate.

120 The means for securing the transparent patch Z to the gripping plate comprises the pair of gripping fingers 19, both of which are fixed to an oscillatory shaft 42, an arm 43 extending from said shaft 42, and a stationary cam 44 adapted to be engaged by a roller on the arm 43. The oscillatory shaft 42 is mounted in the pressure plate 1, and the stationary cam 44 is fixed to the stationary shaft 4. A spring 45 (Figs. II and III) 125 130

connects the arm 43 to a rigid arm 46, the latter being rigidly secured to the pressure plate 1. The spring 45, pulling on the arm 43, tends to close the gripping fingers 19 on the patch Z, but when the parts occupy the positions shown in Fig. III the roller on the arm 43 engages the cam 44 so as to retain the gripping fingers 19 in their open positions. By referring to Fig. II, it will be observed that the gripping fingers 19 lie adjacent to the ends of the transparent patch Z, and the pressure plate 1 is recessed to receive the gripping fingers as shown at 47 in Figs. II and III.

When the patch Z is released from the jaws 22 and 23 the arm 43 passes from the stationary cam 44, and the spring 45 then actuates the arm 43, shaft 42 and gripping fingers 19, so as to force said gripping fingers into the recesses 47, thereby firmly securing the transparent patch to the gripping plate 1.

All of this is accomplished while the gripping plate 1 is traveling continuously in its endless path around the axis of the upper shaft 4. The transparent patch Z is carried to the window opening in the envelop blank X, as shown diagrammatically in Figs. IV and V. When the coöperating pressure plates 1 and 2 pass away from each other, the gripping fingers 19 are actuated to release the blank and patch from the gripping plate 1. This is accomplished when the arm 43 again reaches the stationary cam 44, at which time the arm 43 is actuated by engaging the stationary cam so as to move the gripping fingers 19 away from the pressure plate 1. I have not shown the means for folding and creasing the blank, nor any of the devices to which the blank is delivered after it passes from the pressure plates, for such devices may be constructed in any suitable manner, the present invention being based entirely upon the method of and means for applying the patches to the window openings.

When the pressure plates 1 and 2 occupy the positions shown in Fig. IV, the window envelop blank X is gripped between corners 50 of the opposing plates 1 and 2, and immediately thereafter the pressure plates 1 and 2 are turned on the axes of their pivots 5 so as to lie parallel with each other, as shown in Fig. V. As will be hereinafter described, this is accomplished without stopping or retarding the traveling blank X and without retarding the rotary motion of the carriers 3 to which the pressure plates are pivoted. While the opposing pressure plates are parallel with each other (Fig. V) they travel with the window envelop blank X and its transparent patch Z, thereby firmly forcing the patch into engagement with the blank and maintaining such pressure for a considerable period of time. The patch is there-

fore very firmly secured to the blank and it is not liable to loosen during the subsequent envelop making operations, nor when the envelop is eventually transmitted through the mail. The means for turning the plates 1 and 2 on the axes of their pivots 5 comprises stationary cams 49 (Figs. I and II) fixed to the stationary shafts 4, cam actuated arms 50, pivoted at 51 to the carrier arms 3, each arm 50 being provided with a roller 50', and springs 52 connected to the arms 50 so as to retain their rollers 50' in engagement with the stationary cams 49. When the opposing pressure plates occupy their operative positions on opposite sides 80 of the blank and patch, the rollers 50' associated with said plates travel along the irregular portions of the stationary cams 49, and motion is then transmitted from said rollers to the adjacent arms 50, and thence 85 through links 54 whereby the arms 50 are connected to the pressure plates. The cams 49 and the arms 50 are so constructed and arranged that the pressure plates 1 and 2 will lie parallel with each other during the 90 pressing operations.

While the flat pressure plates are coöperating with each other to press the patch onto the gummed blank, they travel about the axes of the shafts 4, and since said flat plates 95 are parallel with each other during the pressing operation, at least one of the plates must move toward the axis on which it revolves. In other words, if the opposing plates are to lie parallel with each other 100 during the prolonged pressing operation they cannot both travel in absolutely true circular paths. The plates 1 of the rotary carrier A are therefore yieldingly secured to the carrier. Each plate 1 is located adjacent to a plate 1^a provided with pockets 55 for the reception of pins 56 which extend from the plate 1. The pins 56 are slidably mounted in the pockets 55, and secured by headed retaining screws 57 (Fig. II) passing 105 through the end walls of the pockets. Springs 58, arranged in the pockets 55, bear against the ends of pins 56.

The driving mechanism herein shown comprises rotatable sleeves 59 (Figs. II and VI) 115 surrounding the stationary shafts 4, and secured to the arms 3 at one side of the rotary pressure plate carriers. Large gear wheels 60, secured to the sleeves 59, mesh with each other as shown in Fig. VI, and power may 120 be transmitted to these wheels in any suitable manner. The cutting rolls 16 (Figs. I, II and VI), near the upper portion of the machine, are provided with gear wheels 61 which mesh with each other, and a sprocket 125 wheel 62 is secured to a shaft 63 extending from one of the rolls 16. 64 designates a sprocket chain for transmitting power from a wheel 65 on a sleeve 59 to the sprocket wheel 62. The cam 38, for actuating the 130

transferring device, is driven by a chain 66 (Figs. II and VI) which transmits power from a sprocket wheel 67 on the shaft 63 to a sprocket wheel 68 on the cam shaft 39.

5 Fig. VIII is a diagrammatical view illustrating a modification wherein a constantly rotating carrier A', similar to the carrier A, is provided with flat pressure plates 1', corresponding to the plates 1. The pivots 5' 10 correspond to the pivots 5. A constantly traveling endless belt 70 is arranged below the rotary carrier so as to coöperate with the flat plates 1' in applying the transparent patch Z' to the window envelop blank X'. 15 A stationary board or table 71 prevents the belt 70 from sagging under the pressure of the flat plates 1'. In this modified structure, the belt 70 and pressure plates 1' travel with the interposed blank and patch during the 20 pressing operation.

I claim:

1. In a machine for making window envelops, traveling patch applying mechanism comprising a pair of flat faced traveling pressure members whereby the patch and window envelop blank are simultaneously advanced and forced into engagement with each other, rotary means for feeding window envelop blanks to both of said traveling pressure members, means for feeding patches to one of said traveling pressure members, and means for moving said flat faced traveling pressure members in non-circular paths and toward and away from 35 each other.

2. In a machine for making window envelops, traveling patch applying mechanism comprising a pair of traveling pressure members whereby the patch and window envelop blank are firmly forced into engagement with each other, said traveling pressure members being movable toward and away from each other, means for securing patches to one of said traveling pressure 45 members, and means for feeding window envelop blanks into the space between the traveling pressure members.

3. In a machine for making window envelops, traveling patch applying mechanism comprising a pair of traveling flat faced pressure members whereby the patch and window envelop blank are firmly forced into engagement with each other, means for feeding patches to the flat face of one of said traveling pressure members, means for securing the patches to said flat face, and means for feeding window envelop blanks to the traveling pressure members.

4. In a machine for making window envelops, patch applying mechanism comprising oppositely disposed pressure members, means for delivering the blank and patch to said pressure members, said means including feed rolls whereby the blank is fed 65 between said pressure members and a trans-

ferring device whereby the patch is delivered to one of said pressure members, one of said pressure members being movable toward the other to firmly press the blank and patch into engagement with each other, and means for advancing said pressure members in a line parallel with the path of the interposed patch and blank so as to maintain the traveling patch and blank under pressure. 75

5. In a machine for making window envelops, patch applying mechanism comprising oppositely disposed flat faced pressure members, means for delivering the blank and patch to the flat faces of said pressure members, said means including feed rolls whereby the blank is fed between said flat faces and a transferring device whereby the patch is delivered to one of said flat faces, one of said pressure members being movable 80 toward the other to firmly press the blank and patch between the flat faces, and means for advancing said pressure members in non-circular paths with the blank and patch between their flat faces, so as to maintain the 85 traveling blank and patch under pressure.

6. In a machine for making window envelops, traveling patch applying devices revolving about different axes and coöperating with each other to force the patch into engagement with the window envelop blank, each of said traveling patch applying devices including a rotary carrier, a flat faced pressure member pivotally secured to said carrier and means for turning the pressure 95 member on the axis of its pivot, to provide for a non-circular motion about the axis of rotation, the flat faces of the revolving pressure members being parallel with each other when the blank and patch are pressed between them, means for delivering patches to the flat face of one of said pressure members, and means for feeding envelop blanks into the space between said pressure members. 100

7. In a machine for making window envelops, patch applying mechanism comprising flat faced pressure members revolving about different axes and coöperating with each other to firmly press the patch into engagement with the blank, means for feeding patches to one of the pressure members, means for securing the patches to the last mentioned pressure member, and means for feeding window envelop blanks to the flat 115 faces of said pressure members, said pressure members being yieldingly supported and free to remain in parallelism as they travel with the blank and patch during the pressing operation. 120

8. In a machine for making window envelops, patch applying devices comprising coöperating pressure members traveling with the patch and window envelop blank so as to maintain the traveling patch in 130

firm engagement with the traveling envelop blank, means for feeding patches to one of said pressure members, a patch holder carried by the last mentioned pressure member, and means for moving the pressure members toward and away from each other.

9. In a machine for making window envelops, patch applying mechanism comprising flat faced pressure members traveling with the patch and window envelop blank and coöperating with each other to maintain the traveling blank and patch under pressure, rotary carriers to which said flat faced pressure members are yieldingly secured, said rotary carriers being movable about different axes to move said flat faced

pressure members toward and away from each other, a transferring device whereby the patches are delivered to one of said pressure members, a patch gripping device mounted in the last mentioned pressure member, means for closing said patch gripping device on the patch delivered from said transferring device, means for opening said patch gripping device to release the patched blanks, and means for feeding gummed window envelop blanks to the flat faces of the traveling pressure members.

In testimony that I claim the foregoing I hereunto affix my signature.

CHARLES F. PFLANZE.
